CLAIM

The ornamental design for an enteral syringe, substantially
as shown and described.

DESCRIPTION

FIG. 1 is a top-front isometric view of an enteral syringe;
FIG. 2 is a front view of the enteral syringe of FIG. 1;
FIG. 3 is a rear view of the enteral syringe of FIG. 1;
FIG. 4 is a left side view of the enteral syringe of FIG. 1;
FIG. 5 is right side view of the enteral syringe of FIG. 1;
FIG. 6 is a top view of the enteral syringe of FIG. 1; and,
FIG. 7 is a bottom view of the enteral syringe of FIG. 1.
The broken line showing of parts of the drawings is included
for the purpose of illustrating use and environment and
forms no part of the claimed design.

1 Claim, 4 Drawing Sheets
